(57) **CLAIM**

The ornamental design for flatware handle, as shown and described.

DESCRIPTION

FIG. 1 shows a left side elevation view of a flatware handle showing my new design, and mounted on a knife end shown in phantom with broken lines.

FIG. 2 shows a bottom plan view thereof.

FIG. 3 shows a front elevation view thereof.

FIG. 4 shows a cross-section view of FIG. 1 taken along lines 4—4.

FIG. 5 shows a cross-section view of FIG. 1 taken along lines 5—5; and,

FIG. 6 shows a cross-section view of FIG. 1 taken along lines 6—6.

The broken lines in the figures are for illustrative purposes only and are not part of the claimed design.
